UNITED STATES PATENT OFFICE.

FREDERICK WILLIAM LANCHESTER, OF EDGBASTON, BIRMINGHAM, ENGLAND.

MANUFACTURE OF PISTON-PACKINGS.

1,118,784.

Specification of Letters Patent.

Patented Nov. 24, 1914.

Application filed February 7, 1910. Serial No. 542,388.

To all whom it may concern:

Be it known that I, FREDERICK WILLIAM LANCHESTER, of 58 Hagley road, Edgbaston, Birmingham, in the county of Warwick, England, have invented certain new and useful Improvements in the Manufacture of Piston-Packings, of which the following is a specification.

This invention relates to an improved method of manufacturing metallic spring piston rings. The usual method of manufacturing such spring piston rings is broadly to take rings of metal of suitable width, cut out a portion of the circumference of the ring, compress the ring till the ends of the gap abut, and turn or scrape the outside of the now non-circular ring to circular form. It will be seen that this method involves at least three steps, thus, initial turning of the ring, cutting the gap, and final turning or fitting. Now it is found in practice that rings manufactured as above suffer from the defect that the pressure exerted by the ring against the cylinder in which it works is not uniform all around its circumference, and further, that it requires much skill on the part of the mechanic, and the expenditure of considerable time, to obtain a satisfactory fit 30 of such rings in their working cylinders.

The object of the present invention is to reduce the number of processes required in the production of spring piston rings, and to obtain a high degree of accuracy, without the employment of hand fitting.

The present invention consists in a method of manufacturing spring piston rings, which includes the use of a former of such a non-circular figure, that a ring blank shaped from it, when reduced in circumferential extent by the removal of a portion of the circumference, becomes on compression a circular ring of the required finished size.

The present invention also consists in a method of manufacturing spring piston rings, which includes the use of a former, having the non-circular figure obtained by cutting radially a circular ring and inserting a spacing piece in the cut to expand the ring.

The present invention also consists in the method of manufacturing spring piston rings, which includes the use of a former composed of a circular ring, this ring being

cut radially at one place, and sprung open by a spacing piece inserted in the cut.

With reference to the accompanying drawings, Figure 1 is a side view of a form of machine suitable for carrying out the invention. Fig. 2 being an end view, and Fig. 3 a plan of the same. Fig. 4 shows diagrammatically another form of machine, and Figs. 5 and 6 show one method of obtaining the master pattern from which the rings are to be copied.

In carrying the invention into effect according to one mode of operation a former or master pattern is provided, the shape of which is obtained either by calculation or by the springing outward or spreading of a ring of uniform cross section. To construct the former in the latter way, a ring is prepared, preferably of the same diameter as the outside diameter which the finished ring is required to have. This ring is split radially at one place, sprung open, and supported in its sprung position by a gap piece *h* inserted in the cut; the length of this gap piece being such as to provide that when rings made from this former have their ends sprung together, they shall have the proper degree of springiness. The size of this gap therefore depends upon the nature of the material of the ring, and the outward pressure which the ring is required to give, and the length is best found by experiment. After the gap piece *h* has been inserted, the ring and gap piece are clamped between two disks *z*, *z*. These disks are mounted upon a spindle *x*, which is supported in bearings *y*, mounted on the bed of the copying machine, as shown in Figs. 1 and 3. Also mounted upon the spindle *x* is a chuck 2 which carries the blank *b* from which the rings are made. A gearing 3 and 4 rotates the spindle *x*. To the bed of the machine are fitted bearings 5, 5, which carry a shaft *p*. The shaft *p* is free to rotate or rock in the bearings 5, 5. Upon the shaft *p* is keyed an arm *w*, carrying a roller *e* so positioned that the roller *e* can bear upon the former, composed of the sprung ring *a* and the gap piece *h*. Another arm *g* is also keyed to the shaft *p*. Freely journaled upon the shaft *p* is an arm *d*, having an extension *r* passing across and clear of the bed of the machine, and supporting at its end a weight *f* as shown in Fig. 2. A set screw *v* provided in the arm 110

d is adapted to bear against the cranked end of the arm *g*. The effect of this is that the weight *f* tends to pull down the end of the arm *r*, and to move the arm *d* toward 5 the center line of the machine. This movement, however, is limited by the screw *v* bearing against the arm *g*, which is keyed to the shaft *p*. The bearing of the screw *v* upon the arm *g* tends to rotate shaft *p*, but 10 this rotation is controlled by the roller *e* on the arm *w* coming in contact with the former. It is obvious therefore that if the shaft *x*, and consequently the former, is rotated, the arm *w* will be moved to and from 15 the axis of the spindle *x*, according as the radius of the part of the former immediately under the roller *e* is longer or shorter. Upon the end of the arm *d* is provided a bearing *6* carrying a spindle *7*, to one end 20 of which a milling cutter *c* is attached, and to the other end a gear wheel *t*. Two other gear wheels *8* and *9*, carried upon spindles mounted upon the arm *d* connect the wheel *t* with the gear wheel *10*, mounted upon a 25 sleeve *11*, carried freely upon the shaft *p*. Also fixed upon the sleeve *11* are pulleys *s*. If the pulleys *s* are rotated therefore, rotation will be communicated to the milling cutter *c*. 30 The action of the apparatus is as follows:—A blank *b* having been inserted in the chuck *2*, and the machine set in motion, the milling cutter *c* will rotate, removing metal from the blank *b*, as the latter is rotated by the gearing *3* and *4*. The depth to which the cutter *c* can remove 35 metal from the blank *b* is regulated as before stated by the roller *e* following the contour of the former, and thereby controlling the position of the arm *g*, and consequently the cutter *c*. Before cutting off the finished rings, however, it is preferable to submit them to a grinding process, to give a more highly finished surface, the 40 grinding may be done in the same or a similar machine, and conveniently by substituting a grinding wheel for cutter *c*. After having their contour completed, the 45 rings parted off from the blank *b*, are cut radially in two places to remove a gap of 50 the required extent, this gap being proportional to the gap piece *h* inserted in the former.

It will be understood that the inside of 55 the blank may be shaped by a process similar to that by which the outside was cut.

According to another method, the machine may be used as shown in Fig. 4.

According to this modification, two cutting tools *k* and *l* are mounted upon a slide *m*, 60 the tool *k* being adapted to turn the outside of the blank *b*, and the tool *l* the inside of the blank. The slide *m* is connected by a link *12* to an arm *13* pivoted upon a bracket *14* secured to the bed of the machine. The 65 upper end of the lever *13* carries a roller *e*, as in the first modification, of the machine, this roller *e* bearing upon a former *n*, which may be made up in a similar manner to the former already described. The former *n* 70 and blank *b* are mounted upon a spindle, in a similar manner to the first described modification. In the form of machine shown in Fig. 4, the roller *e* is kept in contact with the former by the weight *f* upon 75 the end of an arm *r*, pivoted upon a bracket *15* secured to the bed of the machine. The arm *r* carries a limb *16* having a ball at its upper end adapted to work in a socket upon the slide *m*. 80

It will be obvious that any suitable known form of copying lathe or milling machine may be used for copying the dummy without departing from the scope of this invention.

Having thus described my invention, what I claim as new and desire to secure by Letters Patent is:—

1. A method of manufacturing spring 90 piston rings consisting in making a former of circular form of the finished size of the piston ring, cutting such former in one place, holding such former open to a non-circular form by means of a gap piece, reproducing said non-circular form in metal, 95 and cutting a piece out of said metal ring of equal length to said gap piece, as set forth.

2. A method of manufacturing spring 100 piston rings consisting in making a circular former of the finished size of the ring, cutting said former in one place, holding open said former to a non-circular form by means of a gap piece, forming a blank in a copying machine from said non-circular 105 former, and cutting out from said blank a portion equal in length to the amount by which said former was held open, as set forth.

In testimony whereof I affix my signature in the presence of two subscribing witnesses.

FREDERICK WILLIAM LANCHESTER.
